ROOF OR SIMILAR ARTICLE

Wales E. Ellis, Sr., Oxford, Ga., assignor to Certain-Teed
Products Corporation, Ardmore, Pa., a corporation of Maryland

Filed Feb. 6, 1967, Ser. No. 5,687

Term of patent 14 years

(Cl. D68—1)

The broken lines showing a portion of a building structure in FIG. 3 have been disclosed for illustrative purposes only.

This application is a continuation-in-part of design application Ser. No. 779, filed Jan. 26, 1966 and now abandoned.

I claim:

The ornamental design for a roof or similar article, as shown and described.
